Patented May 25, 1976

239,994

ELECTRIC SHAVE CREAM DISPENSER OR SIMILAR ARTICLE

George H. Fitzsimonds, Bridgeport, Conn., assignor to General Electric Company

Filed Mar. 31, 1975, Ser. No. 563,670

Term of patent 7 years

Int. Cl. D9—01

U.S. Cl. D6—95

Fig. 1.

Fig. 2.

Fig. 5.

Fig. 4.

Fig. 3.

FIG. 1 is a perspective view of an electric shave cream dispenser showing my new design;

FIG. 2 is a top plan view thereof;

FIG. 3 is a front elevational view thereof;

FIG. 4 is a side elevational view thereof; and

FIG. 5 is a rear elevational view thereof.

In FIGS. 1-3, the words which are shown in broken lines are for illustrative purposes only and do not form a part of the claimed design.

I claim:

The ornamental design for an electric shave cream dispenser or similar article, substantially as shown and described.
